UNITED STATES PATENT OFFICE.

JOEL F. BAYMILLER, OF BUHL, IDAHO.

REVOLVING HOUSEKEEPING-CABINET.

1,352,496.

Specification of Letters Patent. Patented Sept. 14, 1920.

Application filed April 19, 1920. Serial No. 375,089.

To all whom it may concern:

Be it known that I, JOEL F. BAYMILLER, a citizen of the United States, residing at Buhl, in the county of Twin Falls and State 5 of Idaho, have invented certain new and useful Improvements in Revolving Housekeeping-Cabinets, of which the following is a specification, reference being had to the accompanying drawings.

10 This invention relates to cabinets, and particularly to revolving cabinets.

Generally speaking, the object of my invention is to economize space in an apartment or house as much as possible, and 15 more particularly to secure this result by the provision in a space between two rooms or in the wall of a room of a revolving cabinet of relatively large size, divided into compartments, as they may be termed, these 20 compartments being arranged and fitted to provide wardrobes, a bed closet, a linen closet, and a kitchen table or any other instrumentalities of this character, the cabinet being made to revolve easily so that any 25 one of these compartments may be brought into position registering with the opening into the room, said cabinet thus forming one of the bounding or defining walls of the room to thus permit a room to be used as a 30 kitchen, dining room or as a bedroom, for instance, depending upon which compartment of the cabinet faces into the room occupied by the user of the cabinet.

A further object is to provide a construction of this kind particularly adapted, as I 35 have designed it, to provide a wardrobe compartment, a cupboard, a table compartment, a linen compartment fitted with shelves and drawers, and a bed compartment.

40 A further object is to provide a structure of this character which is very simple and yet strong, which will turn easily upon its pivotal axis, and in which the closures to the various compartments are paneled so as to 45 not detract from the appearance of the room in general, and in effect constitute one of the defining walls of the room.

Other objects will appear in the course of the following description.

50 My invention is illustrated in the accompanying drawings, wherein:—

Figure 1 is a plan view of a room with my cabinet in place therein, the base frame of the cabinet being shown in plan and the 55 central post in section;

Fig. 2 is a side elevation of the cabinet

partly in section, showing the bed in elevation and lowered and the table 33 in section and lowered;

Fig. 3 is a section on the line 3—3 of 60 Fig. 2;

Fig. 4 is a fragmentary elevation of the lower portion of the cabinet looking toward the linen compartment;

Fig. 5 is a fragmentary detail elevation 65 showing the trunnion of the bed in section and engaged in its socket.

In these drawings, A designates one room and B another room separated by an ornamental partition or arch C having an opening 70 in which the rotating cabinet is disposed. It will be understood that the room B, for instance, might be the size of the cabinet itself so that the cabinet will not project out into the room A but each side of the 75 cabinet will fill the space in the wall C and be flush with the wall, or on the other hand, this cabinet may have its axis disposed in line with said wall. Any of these arrangements of parts is within the purview of my 80 invention.

The base of the cabinet is formed by the pair of diagonally arranged sills 10 which are preferably 2x4 and will be spaced from each other any suitable distance, as for instance 6" to 8", these sills 10 being disposed on either side of a central post 11 which extends vertically through the cabinet and which constitutes a 4"x6" center post or axis. This center post is reduced, as at 12, 90 and at its lower end fits in a bearing 13. This bearing may be a ball bearing and is disposed upon the floor of the house or room. The upper end of the post 12 is reduced in diameter, as at 14, and extends upward to 95 the ceiling of the house. Extending transversely to the sills 10 are the sills 15 which converge inwardly from the opposite corners of the cabinet, these sills being formed by the 2x4 timbers and at their outer ends 100 being separated and attached to spacing blocks 16. The outer ends of the sills 10 are also separated by spacing blocks 17. The corners of the cabinet are flat and at right angles to radial lines drawn from the 105 axial center of the cabinet and are about 8" wide. The sides 10 and 15 are connected by framing sills 9.

The head of the cabinet is formed in the same manner as is the base frame of the 110 cabinet, and these frames are connected at the corners by vertical corner timbers 18,

with the space between them filled by panels. Brace rods 19 may extend from the corners of the floor frame of the cabinet to the central post, in the manner illustrated 5 in Fig. 2, these brace rods being provided with nuts whereby they may be tightened. The corners of the frame below the blocks 16 are provided with caster wheels 20 so as to support the cabinet for easy turning 10 movement.

The head casing is of the same construction as the floor casing, and inasmuch as the cabinet will not extend probably the full height of the room, a stationary paneled 15 closet, designated D, may be formed above the cabinet, through which the central post passes. The height of the cabinet will be something over 6', and the extreme width of one of the spaces will be approximately 20 4½' wide, the cabinet having a diameter of 5½' over all.

I have illustrated my cabinet as being formed to provide a relatively large wardrobe space E, a bed space F, a linen closet 25 with shelves or drawers G, and a kitchen or dining room space H. The bed space F is occupied by a swinging bed 21 consisting of the usual bed frame having the side rails 22, these side rails being pivoted on a trans- 30 verse shaft or trunnion 23 which is disposed preferably in open bearings 24 so that the bed frame may be lifted up when desirable. The frame of the bed is provided at its free end with folding legs 25, these legs 25 being 35 preferably pivoted to the foot of the bed for movement parallel thereto, as illustrated in Fig. 2. The weight of the bed is preferably counterbalanced by counterbalancing weights 26 attached to cords 27 passing over 40 pulleys 28, these cords detachably engaging the bed rails. Of course, it will be understood that these weights are not sufficient to entirely counterbalance the bed, but that they simply relieve some of the weight in 45 lifting the bed up to its closed position. I do not wish to be limited to the particular character of the bed, nor to the details of construction, as it is obvious that these might be varied in many ways without de- 50 parting from the spirit of the invention.

In the space G there is disposed a linen cabinet consisting of upright, shelf supporting members 29 having angle irons 30 at their lower ends and designed to fit within 55 the compartment G so that the frame may be withdrawn therefrom when desired, this being divided by shelves, rails or like elements so as to provide spaces or to provide supports for drawers 31. A certain portion 60 of this linen closet may be formed with shelves and certain other portions with drawers, or the whole of this portion of this compartment may be formed with drawers, as desired.

65 The cupboard section H includes a series

of shelves 32 in the upper part of the compartment supported on vertical timbers at the side of the compartment, this upper shelved portion of the cupboard being normally closed by a swinging member 33 70 hinged to the lowermost shelf and adapted to be turned upward into position to close the cupboard. The outer face of this member 33 is paneled and the upper face constitutes a table when this combined closure 75 and table 32 is turned into a horizontal position. This table is supported by legs 34 hinged to the table and supported by hooked braces 35 when the table is in its lowered position, these hooked braces connecting the 80 table to the legs. When these braces are released, the table may be turned to its vertical position and the legs swung inward so as to form part of the paneling of the table, or to lie in the plane of the table. Below this 85 table are disposed pivoted bins 36 which are normally disposed beneath the lower shelf of the cupboard but which may be swung outward to permit the contents to be taken out. It will be understood, of course, that I 90 do not wish to be limited to the exact arrangement of the parts shown, as the cupboard might be differently arranged and might be arranged in the form of a regular kitchen cabinet, or this cupboard might be 95 used for the purpose of a writing desk and the shelves might support books.

It will be seen that the three compartments heretofore described define a central square space E which opens onto one front 100 of the cabinet, and this central space forms the wardrobe. This wardrobe at the face of the cabinet may be closed by laterally extending, vertical walls 37, this space being filled with shelves 38, and between these 105 walls 37 is the door 39 which is paneled and provided with a mirror 40. The interior of the wardrobe not taken up by shelves is to be provided with transverse rods upon which clothes hangers may be supported and provided with hooks upon which hats and other 110 wearing apparel may be hung.

It will be seen that this wardrobe cabinet, as above described, is particularly adapted for apartment houses, bungalows, and other 115 relatively small living quarters where economy of space is absolutely necessary, and that by its use a person living in one room or two can have many of the conveniences where ordinarily it is impossible to have in 120 such small quarters. When the bed is closed, for instance, the paneled under face of the bed forms part of the paneling of the room A so that the room may then be used as a 125 reception or living room, and it will be also noticed that even when the front of the wardrobe is turned around to the room A, this front being paneled, provided with mirrors, etc., will have a more or less ornamental appearance and will not detract from 130

the appearance of the room. The same is true of the room B if that is more than a mere compartment. Of course, if the walls C come to the cabinet, the cabinet, in order 5 to close the space between said walls, will have to project out into the room.

In the actual construction, the various beams, sills, uprights, etc., forming the frame of the cabinet will be detachably put 10 together by screws, angle irons and bolts so that the entire frame may be readily taken down or put up. The cabinet will be approximately 7' in diameter and approximately 7' high, though it is obvious that 15 the cabinet may be of any desired form. The cabinet may have a very ornamental character or may be severely plain, thus adapting it to cheap constructions or more expensive constructions.

20 While I have illustrated certain details of construction and arrangement of parts, which I have found to be extremely effective, yet it is obvious that many changes might be made therein without departing 25 from the spirit of the invention.

I claim:—

1. A rotatable cabinet comprising a base frame and an upper frame, a central post to which the base frame and upper frame 30 are attached, said post being rotatably mounted, connecting members between the base frame and the upper frame, wheels supporting the outer corners of the frame, said frame being many-sided in cross section and divided by vertical partitions to 35 form a plurality of compartments and opening upon different portions of the cabinet, the central portion of the cabinet defined by the partitions of all but one of the frame 40 constituting a central compartment, this central compartment opening upon one face of the cabinet, a door closing the opening to the central compartment, and members hingedly mounted upon the walls of the 45 other compartments and closing the same and constituting, when closed, the exterior wall of the cabinet.

2. A rotatable cabinet comprising a central, vertically rotatable supporting post 50 and upper and lower frames connecting the post, each of said frames comprising par-

allel, diagonally extending beams and outwardly divergent pairs of beams disposed at right angles to the first named beams, blocks disposed between said beams at their 55 outer ends, upright members connecting the upper and lower frames at their ends, wheels connecting the ends of said beams, said base frame being provided with casters, the cabinet being divided by vertical partitions to provide three vertically extending compartments in the space between said 60 diagonally extending beams and the outwardly divergent beams, these compartments forming three sides of a square, the 65 space defined by the said partitions opening upon the fourth side of the cabinet, and members hinged to the walls of said compartments and adapted to be shifted to close the several compartments and form the 70 outer surface of the cabinet.

3. A rotatable cabinet comprising a central, vertically rotatable supporting post, beams mounted upon the upper and lower ends of the post and extending radially 75 with relation thereto, the upper and lower sets of beams constituting upper and lower frames, vertical members connecting the outer ends of the beams of the upper frame to the outer ends of the beams of the lower 80 frame, vertically extending partitions disposed between the upper and lower frame beams, said partitions defining compartments extending inward from different faces of the cabinet, all of said compartments 85 except one being provided with vertical partitions defining the backs of the several compartments and said backs being spaced from the central post whereby to leave a relatively large central compartment, said 90 central compartment having a door opening in one face of the cabinet, each of said compartments having a hinged member adapted to be turned into a position to close the compartment and form part of the outer 95 wall of the cabinet, those portions of the cabinet between the several compartments being formed with an outer facing.

In testimony whereof I hereunto affix my signature.

JOEL F. BAYMILLER.
